CLAIM

We claim the ornamental design for an aerosol generator, as shown and described.

DESCRIPTION

FIG. 1 is a first perspective view of an aerosol generator showing the claimed design.

FIG. 2 is a second perspective view of the aerosol generator depicted in FIG. 1.

FIG. 3 is a third perspective view of the aerosol generator depicted in FIG. 1.

FIG. 4 is a top plan view of the aerosol generator depicted in FIG. 1.

FIG. 5 is a bottom plan view of the aerosol generator depicted in FIG. 1.

FIG. 6 is a front elevational view of the aerosol generator depicted in FIG. 1.

FIG. 7 is a rear elevational view of the aerosol generator depicted in FIG. 1.

FIG. 8 is a left side elevational view of the aerosol generator depicted in FIG. 1; and,

FIG. 9 is a right side elevational view of an aerosol generator depicted in FIG. 1.

The broken lines in the drawings illustrate portions of the aerosol generator that form no part of the claimed design.
